UNITED STATES PATENT OFFICE.

BOB CATCHINGS, OF JASPER, ALABAMA.

AUTOMATIC AIR-VALVE.

1,049,992.

Specification of Letters Patent.

Patented Jan. 7, 1913.

Application filed April 8, 1910. Serial No. 554,268.

To all whom it may concern:

Be it known that I, BOB CATCHINGS, a citizen of the United States of America, residing at Jasper, in the county of Walker 5 and State of Alabama, have invented new and useful Improvements in Automatic Air-Valves, of which the following is a specification.

This invention relates to an improved automatic air valve adapted to be used in connection with the service pipe of a water system for the purpose of admitting of the entrance or expulsion of atmospheric air, as may be required, and to enable such admittance or expulsion to take place automatically.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the invention may be resorted to when desired.

In the drawing, Figure 1 is a diagrammatic view in elevation, showing several of the improved air valves installed upon a service pipe. Fig. 2 is a vertical sectional view on an enlarged scale of the improved valve.

Corresponding parts in the several figures are denoted by like characters of reference. 40 The improved device comprises a casing A having an intermediate bulged portion 1 from which it tapers upwardly to the neck 2 and downwardly, as shown at 3, toward the base 4 which is exteriorly threaded, as 45 shown at 5, said base being also provided with a bore 6 which is tapered or contracted in a downward direction. The downwardly tapered portion 3 of the casing is to be of considerable length as compared with that 50 portion 7 which tapers upwardly from the intermediate bulging portion or breast 1. The neck 2 is provided with a cap or nipple 8 which may be threaded or otherwise suitably secured thereupon.

55 Disposed within the shell or casing A is a float B, the contour of which is substantially

like that of the outer casing. Said float is provided with a downwardly extending stem 9 projecting into the tapering bore 6 of the base 4, and said float has been shown 60 as provided with small downward projections 10 to prevent it from seating upon the base and thus obstructing the bore 6. Securely mounted upon the upper end of the float B is a cage 11 which extends upwardly into the neck 2 of the casing A, said cage containing a spring 12 bearing at one end against the body of the float and at the opposite end against a follower 13 from which a stem 14 extends upwardly into the 70 nipple 8, said stem carrying a ball-shaped head or valve 15 adapted to obstruct a small aperture 16 in the nipple 8.

The improved device may be mounted upon a service pipe 17 in any desired position adjacent to a faucet 18 upon said service pipe, the connection being made either directly with the pipe, as indicated at A', or by means of a coupling device including a T 19 and an L 20, as shown at A² 80 in Fig. 1 of the drawings.

21 designates the stop cock or valve of ordinary construction adjacent to the lower end of the service pipe.

Assuming the service pipe to be empty and 85 the faucets 18 to be closed, when the stop cock 21 is opened, water will rise in the service pipe and will displace the air contained in said pipe, said air escaping through the apertures 16 of the nipples 8 90 until the water has risen to a point where the floats B in the several casings rise to a point where the apertures 16 will be obstructed. The casings A, however, will still contain a quantity of atmospheric air which 95 under the pressure of the water will become compressed in the upper ends of the casings forming air cushions. The floats will continue to rise until the tension of the spring 12 in each device plus the tension of the air 100 cushion will equalize the pressure of the water. Under these conditions when water is drawn through any of the faucets 18, an even and steady flow will be insured owing to the pressure of the air cushion. 105 Should it be desired to cut off the water, as for instance in cold weather to prevent it from freezing in the pipes, this may be effected without opening the faucets 18 or any of said faucets by simply closing the 110 stop valve 21, when the water contained in the service pipe will escape through the

waste of said stop valve, the water being expelled under pressure of the air forming the air cushions in the several casings A until the floats are lowered to a point 5 where the valves 15 will be unseated, when air will be permitted to enter through the aperture 16 of the nipple.

When the temperature is below the freezing point, if the closing of the stop valve 10 should be neglected, the water in the act of freezing will be displaced upwardly in the tapering casings A, as well as in the tapering bores 6, thus permitting the water to freeze without injury to the fixtures.

15 The improved device, as will be seen from the foregoing description, is simple in construction and entirely automatic in its operation. It may be manufactured and installed at a very moderate expense, and it 20 will be found thoroughly efficient for the purposes for which it is provided.

Having thus described the invention, what is claimed as new, is:—

1. A casing having a bore in the bottom 25 thereof, a float within the casing having a

stem guided in the bore, an apertured nipple at the upper end of the casing, a cage upon the upper end of the float, and a spring actuated follower guided in said cage and having a stem carrying a valve to obstruct 30 the apertured nipple.

2. A tapered casing having an exteriorly threaded bottom member provided with a tapering bore, said casing being provided with an upwardly extending neck, an apertured nipple engaging said neck, a float within the casing having a stem guided in the tapering bottom bore, a cage mounted upon the upper end of the float, a spring actuated follower guided in said cage, and a 40 stem extending upwardly from the follower and having a valve adapted to obstruct the apertured nipple.

In testimony whereof I affix my signature in presence of two witnesses.

BOB CATCHINGS.
